DISPLAY BIER

Philip J. Harrah, Bloomfield, Ind., assignor of
one-half to Chester P. Harrah, Bloomfield,
Ind.

Application June 12, 1934, Serial No. 730,309

5 Claims. (Cl. 27—27)

The object of this invention is to provide a bier for the support and convenient movement of burial caskets, particularly in rooms where they are displayed for sale and it is desired to segregate a particular casket from others in stock, and 5 turn it around from side to side for the critical inspection of customers. It may also be used for the transportation of caskets at funerals, but the chief use will be in display sales rooms.

An important object of the invention is to provide a bier with a main body portion which is supported by transverse end members removably and hingedly attached whereby the ends may be entirely removed with ease or may be swung around against a side of the body portion, to be 10 completely covered by the latter and rigidly attached thereto by brace bars which also serve to attach the ends to the body portion in the transverse positions of the ends.

A further object is to provide a bier which will be inexpensive to manufacture, solid and substantial both in performance and appearance, which is capable of a variety of attractive finishes, and which will be durable and convenient.

I accomplish the above and other objects which will hereinafter appear, by the means illustrated in the accompanying drawing, in which—

Fig. 1 is a top plan view of my invention in operative assembly;

Fig. 2 is a side elevation of the same;

Fig. 3 is an end elevation;

Fig. 4 is a top plan view of the bier in folded condition, also showing one end in dotted lines, partially folded, and

Fig. 5 is a fragment in vertical section on the line 5—5 of Fig. 1 on a larger scale than the other views.

Like characters of reference indicate like parts in the several views of the drawing.

My improved bier is preferably made out of wood in which the main body portion is a paneled frame 6, approximately six feet long and 20 inches in vertical width. The frame comprises a top rail 7 three inches in vertical width and a bottom rail 8, six inches wide, with end strips 9, 9 and intermediate strips 10, 10. Obviously, the above measurements are only illustrative and may be varied without departing from the spirit of my invention.

As the transverse end members 11 and 12 are body supports which are alike in construction and means of attachment to the body 6, a description of one will apply to both and should be so understood.

The end member 11 comprises a pair of vertical posts or legs 13 and 14, here shown as ap-

proximately two inches square in cross section, to which a top frame member 15 and a bottom member 16 are tenoned in the usual manner. The frame thus formed is channeled on the inside to receive a panel 17.

Each end of the main frame 6 is notched at its corners in effect by having the outer vertical edge of the end strip 9 positioned outwardly from the ends of the top and bottom rails 7 and 8, respectively, so that actually, the ends of those rails 7 and 8 terminate back of the outer vertical edge of the end strip 9. These notches receive the respective members 15 and 16 with a close fit therein as indicated in Fig. 5, the upper and bottom edges of the end strip 9 being in contact not only with the respective under and top edges of the side 15 rails 7 and 8 but also extending outwardly under the frame member 15 and over the bottom member 16. The extension of the vertical edge of the end strip 9 beyond the ends of the rails 7 and 8 is made to be such that the vertical edge 5 thereof is in contact with the inner face of the panel 17. Dowel pins 18 and 19 are fixed respectively in the ends of the rails 7 and 8 to extend outwardly and enter suitable sockets in the members 15 and 16 which contact the ends of 10 those rails.

An upper metal brace bar 20 and a lower bar 21 have one end of each bar pivotally attached to members 15 and 16, respectively, and have their other ends pivotally attached to the top rail 30 7 and bottom rail 8 of the main body portion 6 of the bier.

Pivottally secured to the member 15, on the other side of the body portion 6, is a metal brace bar 22, and similarly to the bottom member 16, 35 35 is a brace bar 23. The opposite or inner ends of brace bars 22 and 23 have depending pins 24, riveted to them and by means of which pins the inner ends of bars 22 and 23 are removably secured to the top rail 7 and bottom rail 8 respectively of the body 6, by seating the pins in close fitting sockets 25 formed in the respective rails for that purpose. Duplicate sockets 26 are formed in rails 7 and 8 nearer the middles of said rails to receive the pins of the bier when folded, as 40 45 will be hereinafter particularly described.

Roller castors 27 are attached to the lower ends of the four legs 13, 13 and 14, 14, to enable the bier to be moved in any direction; and to reduce the height of the bier and avoid interference of 50 50 the castors with their supported structure the legs are shortened and the lower corners of the transverse ends are cut away as shown at 28 in Fig. 3, sufficiently, to give clearance for the castor wheels in all positions of the wheels.

Each of the four legs of the bier will preferably be provided with rubber bearings 29 for the direct contact with the caskets which will be supported by and transported on the bier.

- 5 When it is desired to remove the end members 11, all of the metal brace rods are disconnected from the body frame 6, and the members 11 pushed off of the dowel pins and away from the frame 6.
- 10 More generally, however, it is desired to fold the bier into a more compact body, as for transportation and storage.

Assuming that the bier is assembled for use, as shown in Figs. 1 and 2, it may be readily folded by drawing the pins 24, of the bars 22 and 23 out of their sockets. Then the end 11 is pressed out of engagement with the dowel pins, and being thus free to move independently of the body 6 it is swung in the direction shown by dotted lines in Fig. 4, with the bars 20 and 21 acting as hinge bars, to the position shown by full lines in Fig. 4, which position is with the end frame in direct contact with the body 6. Because of the lengths of the bars 20 and 21 the end frame 11 is entirely within the area of the body 6, as shown. That folded position is retained by entering the pins 24 on the bars 22 and 23 in the auxiliary sockets 26.

Changes in form, proportion, size, and the minor details of construction within the scope of the appended claims may be resorted to without departing from the spirit or sacrificing any of the advantages of this invention.

What I claim is—

- 35 1. In a bier, a body comprising longitudinal top and bottom members and vertical members at each end of the body connecting the top and bottom members, a support at each end of the body secured to respective vertical members of the body and both of the supports extending laterally on both sides of said body, and brace bars one on each side of the body hinged at an end of each to a support at points remote from the body and extending diagonally to the body and secured to the body.
- 40 2. In a bier, a body comprising longitudinal top and bottom members and vertical members forming a rectangular frame, rectangular frames one at each end of the body transverse to the body and projecting on each side of the body and removably secured thereto, link bars on one

side of the body hingedly securing the end frames to the body and other link bars on the other side of the body hingedly secured at an end of such link to a transverse frame and having pins at their other ends removably inserted in sockets in the body frame.

5 3. In a bier, a body comprising a rectangular elongated frame notched at the end corners, dowel pins in the notches, supports at the ends of the frame comprising rectangular frames having sockets in the top and bottom members of the frame midway of their ends and receiving corresponding dowel pins of the body frame therein, and diagonal brace bars extending from the end supports to the body.

10 4. In a bier, a body comprising a rectangular elongated frame notched at the end corners, dowel pins in the notches, supports at the ends of the frame comprising rectangular frames having sockets in the top and bottom members of the frame midway of their ends and receiving corresponding dowel pins of the body frame therein, and diagonal brace bars extending from the end supports to the body, the bars on one side of the body of the bier being readily detachable from the body for convenient folding on the other bars as hinges.

15 5. In a bier a body comprising an elongated rectangular frame having vertical members notched at the corners, dowel pins seated in the notches, end supports comprising a rectangular frame with top and bottom frame members between which the end of the body between the notches makes a close fit, said top and bottom end support members having holes in which the 30 dowel pins are seated, brace bars at top and bottom of the body-frame pivotally secured at one end of each brace bar to the respective top and bottom frame members of the end supports, said brace bars extending thence to the body frame 35 to which the other ends of the brace bars are pivotally secured, the bars on one side of the body frame having means for quick and easy detachment of the bars from the body frame 40 to permit the end supports to be folded on the 45 other links into contact with the body frame, said body-frame having auxiliary sockets receiving the pins of the links in folded position of the end supports.

PHILIP J. HARRAH. 50
